Harold Hopkins, Port Chester, N. Y.

Application November 6, 1942, Serial No. 108,715

Term of patent 7 years

To all whom it may concern:

Be it known that I, Harold Hopkins, a citizen of the United States, residing in the town of Port Chester, in the county of Westchester and State of New York, have invented a new, original, and ornamental Design for a Shrine Cabinet or the like, of which the following is a specification, reference being had to the accompanying drawings, forming a part thereof.

Fig. 1 is a front open view of the cabinet showing my design;

Fig. 2 is a front perspective closed view thereof;
Fig. 3 is a vertical cross-sectional view thereof.

I claim:

The ornamental design for a shrine cabinet or the like, substantially as shown.

HAROLD HOPKINS.
